OIL BURNER

Raymond P. Babcock, West Hartford, Conn.

Application May 2, 1934, Serial No. 723,476

6 Claims. (Cl. 158—4)

This invention relates to an improvement in oil burners, and particularly to burners for furnaces for heating homes, but is equally applicable for any purpose requiring the combustion of oil fuel for the creation of heat.

One object of this invention is to so arrange the parts that an electric igniter will be reliable under all circumstances, such as variable draft conditions, freedom from soot accumulating on the electrodes, and so arranging the electrodes that a spark from them will be in the path of the oil spray at all times.

A further object of the invention is to so arrange the parts that the combustion will be very quiet and efficient, so that the flame will be of a gaseous character, and have a lazy slow-burning fire to avoid producing a pulsation, and furthermore to preheat the air before it comes in contact with the fuel.

With these ends in view, my invention consists in the construction as hereinafter described and particularly recited in the claims.

In the accompanying drawing:

Fig. 1 is a side view, partly in section, illustrating an oil burner constructed in accordance with my invention;

Fig. 2 is a sectional view on the line 2—2 of Fig. 1;

Fig. 3 is a perspective view of the combustion-chamber refractory lining, detached; and

Fig. 4 is a perspective view of the refractory baffle-plate, detached.

This device is adapted to be applied to practically any form of furnace into which a refractory lining may be placed. This lining forms a combustion-chamber and is preferably made in sections for convenience of installation. As herein shown, it is formed from two sections 10 and 11, and the space between the lining and the outer wall 12 of the fire box will be filled with insulating material 13.

Within the combustion-chamber is a baffle-plate 14 supported by ribs 15, and this baffle is so formed as to provide an air space around its edges except at the front, where the edges closely fit the refractory lining. Above the baffle-plate 14 is an oil-atomizing nozzle 16 attached to an oil-pipe 17 leading from the source of supply, the nozzle being placed just inside of the refractory lining through an opening 20 formed for it. Above the nozzle are a pair of sparking electrodes 18 and 19, adjusted so as to lie just within the outer edge of the spray of oil from the nozzle, the electric spark being used to ignite the oil at will. The other

ends of the electrodes, of course, extend back to a transformer or supply line.

Air is delivered through a pipe 21 from the usual fan 22 through a notch formed in the lower edge of the refractory lining and below the baffle-plate 14, so as to escape around the edges of the baffle-plate, but is prevented from rising directly in line with the nozzle. The refractory lining is so designed as to completely surround the spray of oil and is built of thin refractory material that will quickly attain a high temperature, thereby causing the oil to pass from the atomized state to a vaporous state before burning, so as to create a slow, lazy, quiet flame. The oil is delivered to the nozzle under sufficient pressure to cause the oil to leave the nozzle in an atomized-spray form, the size of the refractory lining being proportioned to the amount of oil to be burned.

The baffle-plate is so constructed and arranged as to allow the air to be directed in such a manner that it will be released only against the sides of the refractory lining, and also so constructed that no air will be allowed to escape directly underneath the nozzle. By directing the air against the hot walls of the refractory lining, any oil that impinges on the lining will be sure to receive oxygen enough to burn, and by preventing the current of air from being directed against the atomized oil as it is discharged from the nozzle, the oil will be vaporized before receiving the necessary oxygen to cause complete combustion, thereby contributing to a slow, lazy, efficient, quiet flame.

The baffle being of suitable refractory material, will heat quickly and thereby preheat the air, to further assist in gasifying the atomized oil.

The parts as described are so designed as to prevent varying drafts of air over the fire from changing the direction of the oil spray across the path of the electrodes, thus insuring great reliability of the ignition of the fuel at all times.

By properly shaping the combustion-chamber and delivering all or substantially all of the air required for combustion at a point remote from the atomizing nozzle, the combustion which results will not take place in a relatively small cubic space immediately adjacent the said nozzle, but will take place substantially throughout the entire combustion-chamber. Thus, instead of having the intense combustion take place in a relatively small space, as would be the case if the fresh air had immediate access to the jet of atomized oil from the nozzle, the present invention does not deliver the air to the atomized oil until the latter has fully expanded into the com-

bustion-chamber and thus effects mild combustion in a relatively large space. This feature substantially eliminates the roar incident to intense combustion in a small space, since the combustion 5 takes place in a relatively vast space, and consequently in a relatively lazy quiet manner. Furthermore, by delivering the air into the combustion-chamber at locations only remote from the nozzle and electrodes, shifting currents 10 of fresh air are avoided and thus any tendency to deflect the conical stream of atomized oil adjacent the electrode is avoided, thus avoiding varying the ignition effect and also minimizing carbonizing of the electrodes. Attention may also 15 be called to the fact that by causing the walls of the combustion-chamber on the respective opposite sides of the nozzle to substantially conform to the shape of the conical stream of atomized oil emerging from the said nozzle, the leakage of currents of fresh air upwardly between the jet of 20 atomized oil and the wall of the combustion-chamber is substantially prevented, so that the combustion is accomplished slowly substantially throughout the combustion-chamber, rather than 25 very rapidly at a point immediately adjacent the nozzle. It may also be stated that the size of the combustion-chamber is proportioned to the amount of oil which it is desired to burn per hour, so that the slowly-burning oil substantially fills 30 the combustion-chamber.

I claim:

1. An oil-burning apparatus including: a wall surrounding a combustion chamber; an atomizing nozzle arranged to deliver a jet of substantially air-free atomized oil approximately horizontally into said combustion chamber; electric ignition means located immediately adjacent the jet of atomized oil delivered by the said atomizing nozzle; and air-delivery means arranged to 35 deliver air under pressure into said combustion chamber upwardly toward the atomized oil and only at locations at least one third the maximum horizontal dimension of the combustion chamber horizontally away from a vertical line touching 40 the delivery end of the atomizing nozzle; and the portion of the combustion chamber adjacent said nozzle and extending to the nearest location of air-under-pressure delivery being substantially sealed against the admission of air.

50 2. An oil-burning apparatus including: a wall surrounding a combustion chamber; an atomizing nozzle arranged to deliver a jet of atomized oil approximately horizontally into said combustion chamber; electric ignition means located immediately adjacent the jet of atomized oil delivered by the said atomizing nozzle; and air-delivery means arranged to deliver air under pressure into said combustion chamber upwardly toward the atomized oil and only at locations remote 55 from a vertical line touching the delivery end of the atomizing nozzle and immediately adjacent the wall of the combustion chamber.

60 3. An oil-burning apparatus including: a wall surrounding a combustion chamber and having an opening entering, and spaced away from and above the bottom of, said combustion chamber; and an atomizing nozzle and electric ignition means therefor, located in said opening and with said nozzle arranged to deliver a jet of substantially air-free atomized oil approximately horizontally 65 into said combustion chamber, and with the delivery end of said nozzle and the ignition portion of said ignition means within and back from the combustion-chamber end of said opening, and said opening being substantially sealed 70 from the admission of air thereto except at its combustion-chamber end.

against the admission of air thereto except at its combustion-chamber end.

4. An oil-burning apparatus including: a wall surrounding a combustion chamber and having an opening entering, and spaced away from and above the bottom of, said combustion chamber; an atomizing nozzle and electric ignition means therefor, located in said opening and with said nozzle arranged to deliver a jet of substantially air-free atomized oil approximately horizontally 10 into said combustion chamber, and with the delivery end of said nozzle and the ignition portion of said ignition means within and back from the combustion-chamber end of said opening, and said opening being substantially sealed against 15 the admission of air thereto except at its combustion-chamber end; and air-delivery means arranged to deliver air under pressure into said combustion chamber upwardly toward the atomized oil and only at locations remote from a vertical line touching the delivery end of the atomizing nozzle, and the portion of the combustion chamber adjacent said nozzle and extending to the nearest location of air-under-pressure delivery being substantially sealed against the admission 20 of air.

5. An oil-burning apparatus including: a wall surrounding a combustion chamber and having an opening entering said combustion chamber; the said wall having complementary, substantially straight, angularly-disposed, combustion-chamber surface portions extending from said opening and flared horizontally forwardly and laterally outwardly away from each other and from said opening and extending substantially 30 continuously until they meet differently arranged combustion-chamber surface portions remote from said opening; an atomizing nozzle arranged in said opening to deliver a similarly flared jet of atomized oil approximately horizontally into said 35 combustion chamber and along and closely adjacent said angularly-disposed surface portions; ignition means located adjacent the jet of atomized oil delivered by said atomizing nozzle; and air-delivery means arranged to deliver air under 40 pressure into said combustion chamber upwardly toward the atomized oil and only at locations remote from a vertical line touching the delivery end of the atomizing nozzle, and the portion of the combustion chamber adjacent said nozzle and 45 extending to the nearest location of air-under-pressure delivery being substantially sealed against the admission of air.

6. An oil-burning apparatus including: a wall surrounding a combustion chamber and having an opening entering, and spaced away from and above the bottom of, said combustion chamber; an atomizing nozzle and electric ignition means therefor, located in said opening and with the delivery end of said nozzle and the ignition portion of said ignition means within and back from the combustion-chamber end of said opening, and said opening being substantially sealed against 55 the admission of air thereto except at its combustion-chamber end; the said wall having complementary, substantially straight, angularly-disposed combustion-chamber surface portions extending from said opening and flared horizontally forwardly and laterally outwardly away from each other and from said opening and extending 60 substantially continuously until they meet differently arranged combustion-chamber surface portions remote from said opening; said atomizing nozzle being arranged to deliver a similarly flared jet of atomized oil approximately horizontally 65 into said combustion chamber, and with the delivery end of said nozzle and the ignition portion of said ignition means within and back from the combustion-chamber end of said opening, and said opening being substantially sealed against 70 the admission of air thereto except at its combustion-chamber end.

into said combustion chamber and along and closely adjacent said angularly-disposed surface portions; and air-delivery means arranged to deliver air under pressure into said combustion chamber only at locations remote from a vertical line touching the delivery end of the atomizing nozzle, and the portion of the combustion chamber adjacent said nozzle and extending to the nearest location of air-under-pressure delivery being substantially sealed against the admission of air.
